Primary Examiner—M. N. Pandozzi*(74) Attorney, Agent, or Firm*—Wallenstein Wagner & Rockey, Ltd.(57) **CLAIM**

We claim the ornamental design for a rim for cookware, as shown and described.

DESCRIPTION

FIG. 1 is a perspective view of a rim for cookware according to the new design;

FIG. 2 is a front view of the rim for cookware shown in FIG. 1, the rear view and side elevation views being identical thereto;

FIG. 3 is a top view of the rim for cookware shown in FIG. 1;

FIG. 4 is a bottom view of the rim for cookware shown in FIG. 1;

FIG. 5 is a perspective view of another embodiment of a rim for cookware according to the new design;

FIG. 6 is a side elevation view of one side of the rim for cookware shown in FIG. 5, the other side being identical thereto;

FIG. 7 is a front view of the rim for cookware shown in FIG. 5, the rear view being identical thereto;

FIG. 8 is a top view of the rim for cookware shown in FIG. 5; and,

FIG. 9 is a bottom view of the rim for cookware shown in FIG. 5.

The broken lines in the drawings are for illustrative purposes only and form no part of the claimed design.
